UNITED STATES PATENT OFFICE.

PASQUALI STRANO, OF ELIZABETH, NEW JERSEY.

WASHING MACHINE.

Application filed October 3, 1925. Serial No. 60,295.

This invention relates to washing machines and it is an object of the invention to provide a machine of this kind which is adapted to be operated by hand and which is particularly intended for use in connection with the type of stationary tubs now generally in use.

Another object of the invention is to provide a device of this kind which is rectangular in cross section and which has the inner faces of its side walls formed to provide rubbing surfaces together with means carried by the ends of the device for supporting the same for rotary movement.

Another object of the invention is to provide a device of this kind comprising a receptacle having its walls preferably formed of wood together with means coacting with such walls to provide a strong and rigid structure and wherein the liability of the side walls bulging outwardly is substantially eliminated.

It is another object of the invention to provide a device of this kind comprising a receptacle having its ends provided with outstanding stub shafts together with supporting bearings coacting with said shafts which are adapted to be fitted upon the upper edge portions of the walls of a stationary tub or the like.

A still further object of the invention is to provide a device of this kind comprising a receptacle together with means coacting with either end of the receptacle for rotat-

ing the same.

The invention consists in the details of construction and in the combination and arrangement of the several parts of my improved washing machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a longitudinal vertical sectional view taken through a washing machine constructed in accordance with an embodiment of my invention and in applied position;

Figure 2 is a view in perspective of one of

the supporting bearings as herein employed;

Figure 3 is a view in perspective of the second bearing member herein disclosed;

Figure 4 is a view in end elevation of the receptacle comprised in my improved device unapplied;

Figure 5 is a sectional view taken substantially on the line 5—5 of Figure 1.

As disclosed in the accompanying drawings, my improved machine comprises a receptacle R of desired dimensions and which is preferably square in cross section with the walls thereof preferably of wood, such as oak, and having their meeting edge portions securely connected, as at 1, by nails or other preferred attaching members. The side walls of the receptacle R are further maintained in assembled relation by the strengthening bands 2 disposed around the receptacle and preferably at the ends thereof and at a point substantially midway of such ends. One of the side walls of the receptacle R at its central part is provided with a relatively large opening 3 whereby clothing and kindred articles may be readily applied within or removed from the receptacle R, said opening being adapted to be closed by the closure member 4. The closure member 4 has its marginal portions defined by the outstanding flanges 5 which, when the member 4 is in applied position overlie and contact with a gasket 6 of suitable yielding material, said gasket being mounted within a rabbet 7 provided in the outer face of said side wall and defining the opening 3. Adjacent to each end of the opening 3, such wall of the receptacle R is provided with the outstanding blocks 8, the opposed faces of which being provided with the oppositely directed open slots 9 in each of which is adapted to be received an end portion of a holding rod 10, said rod when applied extending lengthwise over the closure member 4.

To further increase the efficiency of this holding rod 10, I find it of advantage to force between the applied rod 10 and closure member 4 a wedge plate 11, said plate 11 when applied assuring the closure member 4 seating in a manner to effect a watertight closure.

The inner face of the applied closure member 4 has disposed thereacross the corrugations or grooves 12 which provide an effective rubbing surface and I also find it of particular importance to provide the inner face of the other side wall of the receptacle R

with the longitudinally disposed grooves or channels 14 for the same purpose.

Secured to the axial center of each end wall 15 of the receptacle R is a circular metallic plate 16 having at its axial center an outstanding stub shaft or trunnion 17 the extremity of which being angular in cross section, as at 18, to permit an operating crank C to be operatively engaged therewith, said crank C being held in applied position by a screw 19 having a winged head 20. Each of the plates 16 has extending radially therefrom and integrally formed therewith the arms 21, said arms being herein disclosed as of a thickness less than the thickness of the plate 16 proper. These arms 21, as herein disclosed, are four in number and of a length to project beyond the side walls of the receptacle R with the possible exception of the side wall provided with the opening 3. These arms 21 are bolted, as at 22, or otherwise attached to the adjacent end wall 15.

The arms 21 coacting with one end wall 15 are complementary to the arms 21 associated with the opposite end wall 15 and each pair of such resultant parallel arms have disposed through their extended portions an extremity of a strengthening rod 23 the extremities of which having engaged therewith the holding nuts 24 contacting with the outer faces of said arms 21. The intermediate or central portion of each of the rods 23 extends over and has contact with an outstanding block 25 arranged substantially at the axial center of the adjacent side wall of the receptacle R and disposed transversely thereof. These rods 23 provide effective means whereby the side walls of the receptacle are effectively maintained in assembled relation and particularly held against bulging outwardly whereby the efficiency of the device is increased and its life materially prolonged.

My washing machine is particularly designed for use in connection with a stationary tub, especially of the type used in connection with the smaller homes, and as illustrated in the accompanying drawings, T 50 denotes a stationary tub of a double type and fitting upon the upper edge of the intermediate or dividing wall 26 is a bracket 27, said bracket being of such a type as to straddle the upper portion of said wall 26 from above. This bracket in cross section is substantially U-shaped in form and its intermediate or base portion 28 is provided with an upstanding open bearing 29 in which may be readily positioned a second stub shaft 30 or trunnion 17. The second stub shaft or trunnion 17 is readily received within an upstanding bearing 30 carried by the intermediate or base portion 31 of a second bracket 32 also substantially U-shaped in cross section and having its inner side mem-

ber 33 continued by the opposite directed elongated arms 34 having close contact with the inner upper portion of an outer or end wall 35 of the tub T, the outer extremities of the arms 34 being provided with the extensions 34 resting upon the upper edge surfaces of the front and rear wall 36 of the tub T as is particularly illustrated in Figure 5 of the accompanying drawings. The arms 34 are of such a length as to fit substantially snug 75 between the front and rear walls 36 so that when turning movement is being imparted to the receptacle R, the bearing 30 is effectively held against movement.

Where the tub is of a single type, two bearing structures similar to that shown in Figure 2 are employed as by having the outer extremities of each of the stub shafts or trunnions 17 provided with the angular portions 18, the crank C may be operatively engaged with either end of the receptacle as the requirements of practice may necessitate or prefer.

In practice, the desired amount of saponified liquid is placed within the receptacle R through the opening 3 together with the clothes and the like to be cleansed. After the closure member 4 has been applied, the receptacle R is rotated resulting in requisite tumbling of the articles within the receptacle 90 to thoroughly clean the same, such cleaning action being facilitated by the internal rubbing surfaces provided by the grooves or channels 12 and 14 hereinbefore referred to. One of the side walls of the receptacle adjacent its junction with a second side wall is provided with an opening 37 normally closed by the plug 38. After the receptacle has been turned for a desired time, the plug 38 will be removed and the water permitted to drain out, it being understood that the side wall of the receptacle in which said opening 37 is positioned then being disposed downwardly so that such water will be received within the tub T and drained off in the usual way. The receptacle R is then partially rotated to bring said side wall to face upwardly whereupon additional water may be placed within the receptacle through said opening 37 and particularly through a hose 110 leading from the faucet F in either of the two tub compartments. The plug 38 is then replaced and the receptacle R again rotated for a desired time. These operations are continued until the water as it passes out through the opening 37 is clean or clear and thus indicating that the articles within the receptacle have been effectively cleansed.

As indicated by broken lines in Figure 5, it is to be noted that the receptacle R is of such dimensions in cross section as to readily rotate within the tub or a compartment thereof without coming in contact with the front wall 36 or with the faucet F.

From the foregoing description it is

thought to be obvious that a washing machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15 I claim:—

In combination with a tub having side walls and front and rear walls, brackets engaged with the upper portions of said side walls and provided with bearings, a closed receptacle having a normally closed opening

in one of its side walls, outstanding stub shafts carried by the ends of the receptacle and engageable with the bearings, means engageable with a stub shaft for rotating the receptacle, said receptacle when in applied position extending across the top of the tub and partially extending therein, each of said bearings being substantially U-shaped in form and straddling a side wall from above, and outstanding arms carried by a side member of one of the brackets, said arms being of a length to fit substantially snug between the front and rear walls of the tub, the outer extremities of the arms being provided with extensions resting upon the upper edge surfaces of the rear and front walls of the tub.

20 In testimony whereof I hereunto affix my signature.
